US0D1008823S

(12) **United States Design Patent** (10) **Patent No.:** **US D1,008,823 S**
(45) **Date of Patent:** **** Dec. 26, 2023**

(54) **TEMPERATURE SENSOR**

- (71) Applicant: **SoCal Dab Tools, LLC**, Boca Raton, FL (US)
- (72) Inventors: **Daniel Wynick**, Boca Raton, FL (US); **Bryan Berc**, North Hollywood, CA (US); **Cody Johnson**, Corona, CA (US); **John Lichtbach**, Whittier, CA (US); **Andrew Habedank**, Washington, MI (US); **Samuel L. Morris, III**, Buffalo, NY (US)
- (73) Assignee: **SOCAL DAB TOOLS, LLC**, Boyton Beach, FL (US)
- (**) Term: **15 Years**
- (21) Appl. No.: **29/816,458**
- (22) Filed: **Nov. 22, 2021**

Related U.S. Application Data

- (63) Continuation of application No. 17/135,323, filed on Dec. 28, 2020, now Pat. No. 11,187,586.
- (51) LOC (14) Cl. **10-04**

CLAIM

The ornamental design for a temperature sensor, as shown and described.

DESCRIPTION

FIG. 1 is a perspective view of a temperature sensor according to a first embodiment of our new design; FIG. 2 is a front elevation view of the temperature sensor shown FIG. 1; FIG. 3 is a rear elevation view of the temperature sensor shown in FIG. 1; FIG. 4 is a right side elevation view of the temperature sensor shown in FIG. 1; FIG. 5 is a left side elevation view of the temperature sensor shown in FIG. 1; FIG. 6 is a top plan view of the temperature sensor shown in FIG. 1; and, FIG. 7 is a bottom plan view of the temperature sensor of FIG. 1; where the bottom plan view is the same. The broken lines shown in the drawings depict portions of the article that form no part of the claimed design.
